UNITED STATES PATENT OFFICE.

WILLIAM H. TOMEY, OF WALLINGFORD, CONNECTICUT, ASSIGNOR TO THE
R. WALLACE & SONS MANUFACTURING COMPANY, OF SAME PLACE.

DESIGN FOR A SPOON, &c.

SPECIFICATION forming part of Design No. 22,501, dated June 6, 1893.

Application filed April 21, 1893. Serial No. 471,344. Term of patent 3½ years.

To all whom it may concern:

Be it known that I, WILLIAM H. TOMEY, of Wallingford, in the county of New Haven and State of Connecticut, have invented a new 5 Design for the Handles of Spoons, Forks, &c.; and I do hereby declare the following, when taken in connection with accompanying drawing and the letters of reference marked thereon, to be a full, clear, and exact description of 10 the same, and which said drawing constitutes part of this specification, and represents a face view.

This invention relates to a design for the handles of spoons, forks and similar articles, 15 and the design consists in the configuration and ornamentation as shown in the accompanying illustration.

The outer end of the handle contains an open field A, which is inclosed by a long 20 scroll B, starting from one side of the center and extending to and downward upon the opposite side a short leaf-like scroll C, and flowers D, the long scroll B being flanked by numerous short leaf-like scrolls E extending

across the top of the spoon and terminating 25 with the scroll B. The remainder of the handle is richly ornamented with numerous small scrolls F, varying in form and curvature, but all belonging to the same rococo style of decoration. A small cluster G of 30 flowers is also seen among the scrolls F, which growing simpler, merge with the handle into the bowl of the spoon. The outline of the handle is slightly broken by the scrolls, particularly at its outer end, but the breaks 35 or irregularities are not pronounced.

I claim—

The design for handles of spoons, forks and like articles, as described and shown in the accompanying illustration. 40

In testimony whereof I have signed this specification in the presence of two subscribing witnesses.

WILLIAM H. TOMEY.
